ATTORNEY.

UNITED STATES PATENT OFFICE.

GUS BECKER, OF FRESNO, CALIFORNIA.

WATCH-CHAIN HOLDER.

Application filed February 26, 1923, Serial No. 621,194. Renewed May 24, 1924.

To all whom it may concern:

Be it known that I, GUS BECKER, a citizen of the United States, residing at Fresno, in the county of Fresno and State 5 of California, have invented certain new and useful Improvements in Watch-Chain Holders, of which the following is a specification.

My invention relates primarily to a device 10 for supporting the center of a watch chain, and the object thereof is to provide a device which can be permanently mounted upon the watch chain, either fixed or loose, which is adapted to be mounted over one 15 of the buttons of the vest and which can be easily and quickly attached to or detached from its place of use and which cannot become accidentally displaced.

Other objects and advantages will appear 20 hereinafter and, while I have shown and will describe the preferred form of my invention, I wish it understood that I do not limit myself to such preferred form but that various changes and adaptations may 25 be made therein without departing from the spirit of my invention.

In the drawings accompanying and forming 30 a part hereof:

Fig. 1 is a view of my device positioned 35 for use.

Fig. 2 is a front elevation of my device detached from its place of use with a fragment 40 of a chain.

Fig. 3 is a central vertical section through 45 Fig. 2.

Fig. 4 is a rear or inside elevation of 50 Fig. 2.

Fig. 5 is a front elevation of another form 55 of my device.

Fig. 6 is a side elevation of Fig. 5.

Referring to the drawings, my device 60 comprises a body member 10 which, in this instance, is substantially circular in front elevation, except at the bottom where it tapers downwardly and inwardly a short 65 distance, and in this tapering portion 11 is provided an aperture 12 in which is slidably mounted the chain 13. Formed in the circular portion of body member 10 is a 70 rearwardly opening annular recess 14 of a size sufficient to receive therein a vest button 15, and extending downwardly from the top wall of said recess 14, parallel with the open 75 edge thereof and at each side of the vertical center thereof, are two flexible securing members 16 and 17 the central portions 18

of which are curved inwardly, as best shown in Fig. 3, and are adapted to bear against the inner side of the button 15 to prevent accidental displacement. Members 16 and 17 have their free ends, in side elevation, flared outwardly to provide a guide for the button 15 when the device is being positioned for use, and in rear elevation, as best shown in Fig. 4, members 16 and 17 are, at 60 a point just below the horizontal center of recess 14, bent inwardly towards each other and then outwardly, the purpose of which will be hereafter explained.

In Figs. 5 and 6 I have shown another 70 form of my device which is similar in all respects to my preferred form with the exception that in lieu of the tapering portion 11 I provide a downwardly depending eyelet 19 through the eye 20 of which the chain may 75 be passed, or a snap ring 21 may be mounted thereon in which the chain may be mounted.

In positioning my device, after the vest has been donned by the wearer in the usual 80 manner and the buttons properly secured, the top edge of the selected button will be inserted between the lower edge of recess 14 and the outwardly flaring ends of members 16 and 17; member 10 will then be pressed downwardly until the button 15 is positioned within recess 14, it being understood 85 that the resiliency of members 16 and 17 will permit their yielding outwardly sufficiently to permit button 15 to pass into recess 14. The inwardly bent portions of 90 members 16 and 17 bearing against the inner face of the button and the thread, or other means by which the button is secured to the vest, will pass between the lower narrowed ends of members 16 and 17 and be 95 held positioned thereby against accidental displacement.

Having described my invention, what I claim is:

1. A watch chain holder comprising a 100 body member adapted to be detachably mounted upon the button of a garment to surround the same except the rear thereof; a pair of spaced resilient securing members extending downwardly from the top wall of 105 said body member adapted to straddle the button securing means and to bear against the inner side of said button; a downwardly depending ear at the lower end of the body member provided with a transverse aperture 110 therein.

2. A watch chain holder comprising a

body member adapted to be detachably mounted upon the button of a garment to surround the same except the rear side thereof; a pair of spaced resilient securing members extending downwardly from the top wall of said body member at the rear thereof, adapted to straddle the button securing means and to bear against the rear wall of said button; and an eyelet extending 10 downwardly from the bottom wall of said body member at a right angle thereto.

3. A watch chain holder comprising a body member substantially circular in front elevation except at the bottom thereof; a 15 downwardly and inwardly tapering portion at the bottom of said body member; an aperture through said depending portion

transversely thereof; a rearwardly opening annular recess in said body member; a pair of downwardly extending flexible securing members at the open edge of said recess extending from the top wall thereof to near the bottom wall, and being provided with an inwardly bowed portion intermediate their length and having their free ends flared outwardly adapted to straddle the securing means of a garment button and to bear against the rear wall of said button.

In witness that I claim the foregoing I have hereunto set my hand this 29th day of January, 1923.

GUS BECKER.
